UNITED STATES PATENT OFFICE.

ALFRED G. F. KUROWSKI, OF BROOKLYN, NEW YORK, ASSIGNOR TO UNDERWOOD TYPE-WRITER COMPANY, OF NEW YORK, N. Y., A CORPORATION OF DELAWARE.

TYPEWRITING MACHINE.

Application filed October 6, 1923. Serial No. 666,907.

To all whom it may concern:

Be it known that I, ALFRED G. F. KUROWSKI, a citizen of the United States, residing in Brooklyn Borough, in the county of Kings, city and State of New York, have invented certain new and useful Improvements in Typewriting Machines, of which the following is a specification.

The invention relates to card-holders, and associated mechanism, for typewriting machines; that is to say, to means whereby without undue bending thereof, cards, such for instance as stencil-cards having relatively stiff marginal strips, may be held to the platen and be line-spaced over the same.

An object of the invention is the provision of novel and simple means for detachably securing the card-holder and associated parts to the platen-frame, so that, with expedition and with little or no trouble, it may be applied as a unit to the machine when its use is desired and be dismounted therefrom when the machine is to be used for other purposes; all without modification of standard parts of the machine.

A further object of the invention is the provision of novel and simple means for line-spacing the card-holder from the mechanism normally employed to line-space the platen; and in this connection a feature of the invention, in the preferred form thereof, is the provision of means whereby the line-spacer may be rendered ineffective to line-space the platen and nevertheless be utilized to line-space the card-holder, when the latter device is applied to the machine.

A feature of the invention is a clamp for securing to the card-holder a celluloid backing for the stencils, and for securing the backings in such manner that the same may be quickly and easily placed and replaced on the card-holder.

Another feature of the invention is the provision on a card-holder, of the general character mentioned, of adjustable side-marginal gages for the cards.

Another feature of the invention relates to a curved formation of the upper reach of the card-holder-frame to provide clearance for the operator's fingers in the insertion and removal of cards.

A feature of the invention is the provision of means on the card-holder for preventing

bulging or bending of the cards between the side-margins thereof.

A feature of the invention is the provision in a front-strike typewriting machine, having front-pressure or feed-rolls below the printing line, of a detachable card-holder movable across the place normally occupied by such front rolls, and of means for displacing such rolls from their normal position preliminary to placement of the card-holder on the machine.

Other features and advantages will hereinafter appear.

In the accompanying drawings,

Figure 1 is a view, in front elevation, of the platen-frame and associated parts of a typewriting machine embodying the present invention.

Figure 2 is a top plan view of the apparatus shown in Figure 1.

Figure 3 is a view, in perspective, of the left-hand side of the card-holding device.

Figure 4 is a view, in left-hand end elevation, of the card-holding device in its normal or idle position on the platen-frame, preliminary to commencement of stenciling.

Figure 5 is a view similar to Figure 4, except that the card-holding device has been line-spaced upward and the line-space mechanism is shown as in the act of completing the last upward feed of the stenciling device.

Figure 6 is a view, in left-hand elevation, taken on the line 6—6 of Figure 1.

Figure 7 is a view, in end elevation, showing more particularly the parts of the line-space mechanism for line-spacing the platen.

Figure 8 is a view of the left-hand end of the platen-axle showing the clutch device for connecting and disconnecting the platen to and from the line-space mechanism.

The platen 10 is fixed to an axle 11 journaled in the side plates 12 of the platen frame. The platen may be rotated by means of the usual finger-wheels 13, or by means of a line-space ratchet-wheel 14. The latter may turn freely without movement of the platen, or may be locked to the platen-axle to cause the platen to have line-feed rotation when the line-space mechanism is operated. A finger-piece 15, movable in and out longitudinally of the left-hand end of the platen-axle, operates a clutch-device, not shown, for locking the ratchet-wheel to the platen and for releasing the platen from the line-space

mechanism. This clutch-device may be that shown in United States Letters Patent to Helmond, No. 1,150,366, dated August 17, 1915, and so is not described in detail here. The line-space mechanism for rotating the ratchet-wheel 14, which may be that found in the Underwood standard typewriting machine, comprises a slide or plunger 17 movable forward and backward on the left-hand frame-piece 12 and carrying a pawl 18 for engagement with the teeth of the ratchet-wheel. A spring 19, secured at 20 to the slide 17 and secured at 21 to the side piece 12, acts to hold the slide forward in its normal position and to return it to such position when free to do so. A line-space lever, in the form of a bell-crank 22 pivoted at 23 to the side piece 12, has one arm 24 thereof disposed for engagement with an offset 25 on the forward end of the slide 17; so that, when the lever 22 is thrown to the right, the slide is moved back against the action of the spring 19 to effect line-feed of the ratchet-wheel. A spring-detent 26, by engagement with the teeth of the ratchet-wheel, holds the latter against accidental rotary displacement.

On the platen-frame, at the rear of the platen, is the usual paper-table 27, which is continued in the form of an apron 28 around under the platen for rear insertion of work-pieces in the ordinary use of the machine. The usual front and rear pressure-rolls 29 and 30 co-operate with the platen to feed the work-pieces in the ordinary use of the machine. These pressure-rolls are on rear shaft 31 and forward shaft (not shown) demountably supported in the arms of levers 33 and 34, pivoted on a shaft 35 which is carried by the end pieces 12 of the platen-frame; so that, by rocking these levers, the pressure-rolls may be released from the platen and thrown to the platen. The mechanism whereby the pressure-rolls are released and reapplied may be that shown in United States Letters Patent to McLaughlin, No. 739,102, dated September 15, 1903, to which reference is made for such detailed explanation thereof as may be desired. Suffice here to say that the lever 33 comprises an arm 36, and the lever 34 an arm 38, which normally rest on the opposite side of flats cut into a rock-shaft 37, which latter shaft may be turned by connections to a finger-piece conveniently located on the platen-frame. The structure is such that, after the pressure-rolls have been thrown off the platen by the mechanism referred to, the roll-supporting fingers 34 may be given a farther downward and forward pull to a position permitting the front-pressure-roll shaft to be lifted therefrom, so that, as hereinafter explained, the front pressure-rolls may not

interfere with the positioning and movement of the card-holding device when the machine is to be transformed from its ordinary uses to the use thereof for stenciling.

As hereinbefore mentioned, the card-holding device, including all parts thereof and actuating mechanism therefor, may be affixed as a unit to the platen-frame and removed as a unit therefrom, according to the intended use of the machine. It therefore has its own frame-members, which consist of flat end plates 39 which are tied together by a rod 40, adapted to be set upon the usual flat upper offsets or flanges 41 of the side pieces 12 of the platen-frame. The card-holder frame-plates 39 are centered on the platen-frame-plates 12 by means of studs 42, which are affixed to and project upward from the flanges 41 of the plates 12, and which pass through holes in the plates 39. The studs 42 are undercut to receive blades 43, pivotally mounted at 44 on the plates 39. These blades may be swung laterally free of the studs 42 to permit the removal of the frame-plates 39 of the card-holding device; but, when the card-holding device is in place, are held in the position shown in Figure 2, to lock the card-holding device to the platen-frame, by means of springs 45 which connect down-turned ears 46 on the blades with down-turned ears 47 on the frame-plates 39, and thus maintain the blades in the undercuts of the studs 42. By means of finger-pieces 48 on the blades, the same may be rocked laterally within the limits defined by a pin-and-slot connection 49 of the blades to the plates, to unlock the forward ends of the plates 39 from the platen side pieces. Thumb-screws 50, passed through holes in the card-holder frame-plates 39, near the rear thereof, and threaded into the platen-frame side pieces, may be used to hold the card-holder frame at its rear to the platen-frame. When the screws 50 are removed and the blades 43 rocked laterally, the entire card-holder frame may be lifted from the platen-frame by means of finger-pieces or ears 51 on the card-holder frame. In the seating of the card-holder frame on the platen-frame, the locking blades 43 are automatically rocked outward by the conical or cam-shaped ends of the studs 42, so that, when the blades register with the undercuts, the springs 45 act automatically to lock the frames together upon mere downward pressure of one frame upon the other.

Journalized in depending ears 52 on the side plates 39 of the card-holder frame is a rock-shaft 53. Fast on the rock-shaft 53 are a pair of arms 54 (see Figures 2, 3 and 6), which extend up from the rock-shaft 53 and thence forwardly well above the platen. The forward ends of the arms 54 are turned downward, as at 55. A

frame 56, on which the stencil-cards are directly supported, has upturned ears 57 at the ends thereof, by means of which it is pivotally mounted at 58 on the ends 55 of the arms 54. Coil-springs 59, secured at one end to lugs 60 on ears 57, and at the other end to pins 61 on the arms 54, serve to hold the frame 56 in such position that the stencil will properly lie against the platen. Stop-pins 62 on the lugs 60, by engagement with shoulders 63 on the arms 54, determine the desired setting of the stencil-frame with respect to the platen.

The stencil-frame comprises an upper cross-reach 64, having a central upper bend 65 therein to permit of insertion of the operator's fingers for placement or removal of a stencil-card. On the cross-reach 64, at each side thereof, is a forwardly-extending ear 66 of the general curvature of the platen; and secured to the ears 66 are the laterally-projecting ears 67 of a plate comprising side pieces 68 which extend forward and downward to follow the general curvature of the platen so as to be set snugly thereto. At their lower ends the side pieces 68 have soldered to the front face thereof a thin metal strip 69, which forms a cross-reach and ties together the side pieces 68 into a single plate. The side pieces 68, together with the upper cross-reach 64 and the lower cross-reach 69, therefore, form a frame with an opening therein which is rectangular except for the bend 65, for the operator's fingers, at the upper portion thereof. The plate forming the lower cross-reach 69 of this frame is turned rearwardly around the lower edges of the side pieces 68, and is thence turned upward at 70 to form a pocket or seat for the stencil-cards; the upturned lip of this pocket-piece 69-70 being spaced sufficiently from the rear faces of the frame-members 68 to permit of easy insertion of the stencil-cards therebetween.

45 A celluloid backing-piece is employed in conjunction with the card-holding frame 56, 68-69. This celluloid backing-piece 71 (see Figure 6) rests at its lower edge against the rear face of the pocket-piece 70, and has 50 its upper edge 72 substantially flush with the upper edge of the cross-reach 64. It is locked to the rear face of the latter, at each side, by means of a clamp. Each of such clamps comprises a plate 73 set upon the cross-reach 64 and pivoted to the latter at 74. Each plate 73 has an ear 75 (see Figures 3 and 6), which is bent around the upper edge of the cross-reach 64, and which has a downturned portion 76 sufficiently 55 spaced from the rear face of the cross-reach 64 to receive the upper edge of the celluloid backing-piece therebetween. When, by means of a finger-piece 77, the clamp-plate 73 is swung upward on its pivot 74, the 60 parts are in position for insertion of the

celluloid backing. Upon movement of the clamp to the Figures 3 and 6 position, the celluloid is locked in place solely by its upper edge, since the lower edge bears loosely, as aforesaid, against the pocket-member 70. 70 A detent 78 on each clamp-plate 73, by engagement with a corresponding recess in the cross-piece 64 of the card-holder, holds the clamp in locking position. The upper edge of the celluloid backing-piece is cut away 75 at 79 so as not to obstruct the insertion of the operator's fingers behind the upper margin of the stencil-card, for insertion or removal of the latter.

80 A stencil-card 80 is shown in position in the card-holder. This stencil-card comprises a rectangular cardboard frame 81, to the rear of which is pasted the stenciling sheet 82. When the card is in position, with its lower edge seated in the pocket 69-70 and 85 with its side margins in proper position, the stenciling sheet 82 is seen through the card-holder frame 56, 68-69, and is in position to receive type impressions. The celluloid backing-piece forms with the frame members 68, 69 a pocket into which the stencil-card is easily insertable. In inserting the stencil-card, it is passed down in front of the upper cross-reach 64 of the card-holder frame, and thence down behind the side 90 reaches 68. From the upper portions of the side members 68 fingers 83 are turned laterally toward each other to overlie the upper margin 84 of the stencil-card and prevent the latter from bulging between the sides of the card-holder. When the cards are thrust down into home position in the card-holder, they may be held against upward displacement by means of detents in the form of 95 spring-fingers 85, which are bent backward at 86 to overlap the upper edge 87 of the card. The spring action of these fingers causes the same to snap over the cardboard margin of the stencil-card at the proper time. The detents are turned forward at 88, 100 at their upper edges, so that the card, upon insertion thereof, will cam the fingers back from its path.

105 The spring-detents 85 are formed on plates 89, secured by screws 90 to the ears 66 on the card-holder frame-member 56. The plates 89 have also rearwardly-turned ears 91 which serve as side-marginal gages for the stencil-cards (see Figures 2 and 3). To accommodate the card-holders to cards 110 of different widths, the plates 89 are adjustable longitudinally of the platen on the ears 66 of the card-holder frame. To this end, the plates 89 are slotted, as at 92, to receive screws 90 on the ears 66. When these screws are loosened, the plates 89 are movable to desired position and are then locked in 115 such position by tightening the screws.

120 It has been stated that the arms 54 of the card-holder are on the rock-shaft 53. This 125

130

is to permit the card-holder to be line-spaced upward around the axis of the shaft 53. The curvature of the card-holder is such as to hold the card properly to the platen, between the latter and the usual type-bar guide, in any angular position of the arms 54. In Figure 6, the card-holder is shown as having been swung down so that the type 95 may write on the upper portion of the latter. The card is shown as of such length that at least five lines may be written thereon as the card-holder is progressively stepped or line-spaced upward.

To effect such line-space movement of the card-holder from the platen line-space mechanism heretofore described, the following mechanism is employed. Fast on the shaft 53 is a segmental ratchet-plate 96. Loosely pivoted on the shaft 53 is an arm 97 having pivoted thereto, at its forward end, a pawl 98 for engagement with the teeth 99 on the plate 96. A coil-spring 100, connected to the arm 97 and to the pawl 98, when free to do so, throws the pawl into engagement with the teeth, and holds the same in operative engagement with the teeth. When the arm 97 is forced to its lowermost position, however, a dog 101 on the pawl, by engagement with a pin 102 on a bracket 103 depending from the side piece 39 of the card-holder-frame, causes the pawl to be rocked and held out of engagement with the teeth 99. A leaf-spring 104, bearing on the upper edge of the arm 97 and secured to a pin 105 on the card-holder-frame side piece 39, presses down the arm 97 to release the pawl 98 from the teeth 99 and to hold the pawl normally out of engagement with the teeth 99 against the action of the spring 100; the leaf-spring 104 being sufficiently stronger than the spring 100 to effect this result.

The arm 97, at its forward end, is turned up at 106, and is thence turned leftward at 107, and downward at 108, to form a U (see Figures 1 and 5). The downturned portion 108 of this U member (see Figure 4) normally lies in the path of rearward movement of the offset 25 on the forward end of the platen line-space-slide 17. This downturned 50 U portion 108 has also an inclined or cam edge 109, against which the slide 17 acts when the same is thrust rearward. It follows that, upon rearward thrust of the slide 17 on operation of the line-space lever 22, the arm 97 is rocked upward, as shown in Figure 5, against the action of the leaf-spring 104. The first effect of this upward movement is to release the pawl so that it may engage the teeth 99 on the segment-plate 96. Thereupon, the forcible upward movement of the arm 97, by means of the slide 17, causes the segment-plate 96 to move up, and, by means of the shaft 53 to which it is fast, to correspondingly move up the card-holder. This upward movement will be a

one-step line-space movement. Upon release of the line-space lever, the spring 104 throws the arm 97 back to its normal position; that is to say, into position for engagement of the pawl 98 with the next succeeding tooth 99 upon the next operation of the line-space lever. A spring-detent 110, by engagement with the teeth 99, may serve to hold the segment-plate 96 and card-holder, against accidental displacement, in the position to which they have been line-spaced. After stenciling on a card has been completed, and when the stencil-card has been removed and replaced by another card, the card-holder, together with the segment-plate 96, may be thrust down, from Figure 5 to Figure 4 position, by means of a finger-piece 111 on the segment-plate 96, or by means of finger-pieces 112 on the card-holder-supporting arms 54. The Figure 4 position of the card-holder may be determined by engagement of the pin 105 on the card-holder frame side piece 39 with the upper end of a slot 113 in the segmental ratchet-plate 96. Movement of the card-holder with the card to this lowermost position is not obstructed by the front pressure-rolls, because, as heretofore explained, these rolls have been removed preliminary to the use of the machine with the card-holder. Engagement of pin 105 with the lower end of the slot 113 may determine the uppermost position to which the card-holder may be moved.

As line-space movement of the platen is unnecessary in the use of the present invention, the ratchet-wheel 14, as hereinbefore suggested, may be unlocked from the platen so that operation of the line-space lever 22, to line-feed the card-holder, will have no effect upon the platen. This makes easier the effort of line-spacing the card-holder, and permits the rear pressure-rolls to be left in their normal position against the platen.

Variations may be resorted to within the scope of the invention, and portions of the improvements may be used without others.

Having thus described my invention, I claim:

1. In a typewriting machine, a cylindrical platen, a card-holder curved over the face of the platen, means for pivotally supporting the card-holder behind the platen, a segmental ratchet fast to the machine-frame, a pawl-carrying arm for line-spacing the ratchet with the card-holder, and mechanism for line-spacing the platen comprising means for actuating the line-space-arm of the card-holder.

2. In a typewriting machine, a cylindrical platen, a card-holder curved over the face of the platen, means for pivotally supporting the card-holder behind the platen, a segmental ratchet fast to the machine-frame, a

5 pawl-carrying arm for line-spacing the ratchet with the card-holder, mechanism for line-spacing the platen comprising means for actuating the line-space-arm of the card-holder, and means for rendering the platen-line-spacing mechanism ineffective on the platen while the same remains effective on the card-holder.

3. In a typewriting machine, a cylindrical platen, a card-holder curved over the face of the platen, means for pivotally supporting the card-holder behind the platen, a segmental ratchet fast to the machine-frame, an arm pivoted for movement with respect 10 to the ratchet and carrying a pawl for engagement with the ratchet, and a plunger for engagement with the arm to rock the same, and thereby effect line-space-movement of the ratchet with the card-holder.

20 4. In a typewriting machine, a cylindrical platen, a card-holder curved over the face of the platen, means for pivotally supporting the card-holder behind the platen, a segmental ratchet fast to the machine-frame, an arm pivoted for movement with respect to the ratchet and carrying a pawl for engagement with the ratchet, and a plunger for engagement with the arm to rock the same, and thereby effect line-space-movement of the ratchet with the card-holder, the pawl-carrying arm having a cam thereon in the path of the plunger, and by 25 means of which the arm is actuated by the plunger.

35 5. In a typewriting machine, a cylindrical platen, a card-holder curved over the face of the platen, means for pivotally supporting the card-holder behind the platen, a segmental ratchet fast to the machine-frame, an arm pivoted for movement with respect to the ratchet and carrying a pawl for engagement with the ratchet, a plunger for engagement with the arm to rock the same, and thereby effect line-space-movement of the ratchet with the card-holder, a spring for returning the arm to normal position 40 after each line-space-movement thereof, and a stop against which the pawl is thrown and released from the ratchet upon movement of the pawl-carrying arm by the spring.

60 6. In a typewriting machine, a cylindrical platen, a card-holder curved over the face of the platen, means for pivotally supporting the card-holder behind the platen, a segmental ratchet fast to the machine-frame, an arm pivoted for movement with respect to the ratchet and carrying a pawl for engagement with the ratchet, a plunger for engagement with the arm to rock the same, and thereby effect line-space-movement of the ratchet with the card-holder, a spring for returning the arm to normal position after each line-space-movement thereof, a 65 stop against which the pawl is thrown and

released from the ratchet upon movement of the pawl-carrying arm by the spring, and a weaker spring for throwing the pawl to the ratchet upon such movement of the arm with the pawl as clears the pawl from the stop.

7. In a typewriting machine, a cylindrical platen, a card-holder curved over the face of the platen, means for pivotally supporting the card-holder for movement in line-space and return directions over the face of the platen, a segmental ratchet fast to the machine-frame, a pawl-carrying arm for line-spacing the ratchet with the card-holder, a cam on the arm, and a plunger for engagement with the cam to rock the arm in line-space direction.

8. In a typewriting machine, a cylindrical platen, a frame for the platen, a card-holder curved over the face of the platen, a frame for the card-holder, a rock-shaft on the card-holder-frame, means by which the card-holder is made fast to the rock-shaft, a segmental ratchet fast to the machine-frame, a pawl-carrying arm loosely pivoted on the rock-shaft for line-spacing the ratchet with the card-holder, and means for actuating the arm.

9. In a typewriting machine, a cylindrical platen, a frame for the platen, a card-holder curved over the face of the platen, a frame for the card-holder, a rock-shaft on the card-holder-frame, means by which the card-holder is made fast to the rock-shaft, a segmental ratchet fast to the machine-frame, a pawl-carrying arm loosely pivoted on the rock-shaft for line-spacing the ratchet with the card-holder, means for actuating the arm, and means for detachably securing the card-holder-frame with the elements thereon as a unit to the platen-frame.

10. In a typewriting machine, a cylindrical platen, a frame for the platen, a card-holder curved over the face of the platen, a frame for the card-holder, a rock-shaft on the card-holder-frame, means by which the card-holder is made fast to the rock-shaft, a segmental ratchet fast to the machine-frame, a pawl-carrying arm loosely pivoted on the rock-shaft for line-spacing the ratchet with the card-holder, and a plunger movable backward and forward on the platen-frame for actuating said arm.

11. In a typewriting machine, a cylindrical platen, a frame for the platen, a card-holder curved over the face of the platen, a frame for the card-holder, a rock-shaft on the card-holder-frame, means by which the card-holder is made fast to the rock-shaft, a segmental ratchet fast to the machine-frame, a pawl-carrying arm loosely pivoted on the rock-shaft for line-spacing the ratchet with the card-holder, and a plunger movable backward and forward on the platen-frame.

frame for actuating said arm, the arm having a cam thereon in the path of the plunger, and by means of which the plunger actuates the arm.

5 12. In a typewriting machine, a cylindrical platen, a frame for the platen, a card-holder curved over the face of the platen, a frame for the card-holder, a rock-shaft on the card-holder-frame, means by which the

10 card-holder is made fast to the rock-shaft, a segmental ratchet fast to the machine-frame, a pawl-carrying arm loosely pivoted on the rock-shaft for line-spacing the ratchet with the card-holder, and line-space mechanism for the platen comprising a plunger for actuating said arm.

13. In a typewriting machine, a cylindrical platen, a frame for the platen, a card-holder curved over the face of the platen,

20 a frame for the card-holder, a rock-shaft on the card-holder-frame, means by which the card-holder is made fast to the rock-shaft, a segmental ratchet fast to the machine-frame, a pawl-carrying arm loosely pivoted

25 on the rock-shaft for line-spacing the ratchet with the card-holder, line-space mechanism for the platen comprising a plunger for actuating said arm, and means for rendering the plunger ineffective to line-space

30 the platen while maintaining the same in effective relation for actuating said arm.

14. In a typewriting machine, a cylindrical platen, a stencil-card holder mounted for line-space movement with respect to

35 the platen, means for releasably clamping a celluloid backing sheet to the card-holder, between the stencil-card and the platen, and means for line-feeding the card-holder relatively to the platen, such clamp comprising

40 an arm pivotally mounted on the card-holder, and having a clip adapted to embrace one edge of the card-holder and a corresponding edge of the celluloid backing when the arm is rocked to effective position.

45 15. In a typewriting machine, a platen, a card-holder mounted for line-space-movement with respect to the platen, means for clamping a celluloid backing sheet to the card-holder, such clamp comprising an arm

50 pivotally mounted on the card-holder, and having a clip adapted to embrace one edge of the card-holder and a corresponding edge of the celluloid backing when the arm is

rocked to effective position, and a detent on the arm for automatically locking the arm in effective position against accidental displacement.

55 16. In a typewriting machine, a platen, a card-holder mounted for line-space-movement with respect to the platen, means for clamping a celluloid backing sheet to the card-holder, such clamp comprising an arm pivotally mounted on the card-holder, and having a clip adapted to embrace one edge of the card-holder and a corresponding edge of the celluloid backing when the arm is rocked to effective position, and a detent on the arm for automatically locking the arm in effective position against accidental displacement, by spring-pressure into a hole in

70 the card-holder.

17. In a typewriting machine, a platen, a card-holder mounted for movement in line-space and return directions over the face of the platen, and adjustable side 75 marginal gages for the cards on the card-holder, such side marginal gages having affixed thereto spring-clips adapted to snap over the upper edge of the card, automatically to lock the card in place in the holder

80 when the latter is thrust home therein.

18. In a typewriting machine, a cylindrical platen, a frame for the platen, a card-holder, means for supporting the card-holder on an axis behind the platen for 85 oscillatory movement in line-space and return directions over the face of the platen, whereby the card-holder may also have movement inward and outward toward and from the face of the platen, properly to 90 seat itself with respect to the platen, and resilient means for urging the card-holder toward the platen, properly to seat itself with respect to the latter.

95 19. In a typewriting machine, a cylindrical platen, a frame for the platen, a card-holder, a shaft behind the platen, and arms on the shaft for supporting the card-holder for oscillatory movement in line-space and return directions over the face of the platen, the card-holder being pivotally connected to the arms for movement toward and from the face of the platen, properly to be seated with respect to the latter.

ALFRED G. F. KUROWSKI.
